UNITED STATES PATENT OFFICE.

CHARLES METCALF, OF STREATOR, ILLINOIS.

VACUUM VAPOR DAMPER-REGULATOR.

1,294,360.

Specification of Letters Patent. Patented Feb. 11, 1919.

Application filed May 21, 1917. Serial No. 169,859.

To all whom it may concern:

Be it known that I, CHARLES METCALF, a citizen of the United States, residing at Streator, in the county of La Salle and State 5 of Illinois, have invented a certain new and useful Improvement in Vacuum Vapor Damper-Regulators, of which the following is a full, clear, concise, and exact description, reference being had to the accompanying 10 drawings, forming a part of this specification.

This invention relates to improvements in vacuum vapor damper regulators.

In connection with vacuum heating systems, it is now customary to employ a regulator having a bellows-controlled member for actuating the damper proper, the interior of the bellows being in communication with the heating system so that the bellows 15 contracts and expands in accordance with variations in the vapor pressure of the system. Heretofore, so far as I am aware, no means have been provided for limiting the amount of contraction of the bellows (which 20 are ordinarily made of thin sheet metal) with the result that when extreme vacuum occurs in the system, the bellows are contracted to such an extent as to collapse and render them useless.

30 The object of my invention is to provide a damper regulator of the type above referred to wherein means are employed for positively limiting the degree of contraction of the bellows regardless of the degree of 35 vacuum in the heating system, to thus protect and save the bellows with a consequent saving in the cost of repairs and replacements.

Another and more specific object of the 40 invention is to provide a regulator of the type hereinbefore referred to wherein is employed a check or relief valve for the purpose of equalizing the pressure in the system with that in the bellows as the pressure within 45 the system rises to a point where the damper regulator is set to operate.

Another object of the invention is to provide a regulator of the type set forth in the two preceding paragraphs which shall be of 50 simple construction, relatively cheap to manufacture, and which can be installed with a minimum of effort.

In the drawing forming a part of this specification, is shown a central, vertical, 55 sectional view of an improved regulator embodying my invention.

In said drawing, 10 denotes a sheet metal bellows of usual form, the same being secured at its lower end to a base casting 11 having a depending interiorly threaded 60 bushing 12. Threaded within the bushing 12 is the upper end of a nipple section 13, the lower end of said nipple section 13 being threaded as indicated at 14 and adapted to be screwed into a boiler or other portion of 65 a vacuum heating system to thereby place the interior of the bellows in communication with the vapor system. The nipple section 13, preferably near the lower end thereof, is provided on its interior with a conical valve 70 seat 15 with which is adapted to coöperate what may be termed a main valve 16, said main valve 16 being carried by a hollow tube 17 that extends through the enlargement 18 formed on the interior of the nipple section 75 and by which the tube is guided. Said tube 17, at its upper end, is threaded to a depending boss 19 formed on a damper actuating member 20. Said member 20 is provided with a beveled upper edge, as indicated at 80 21, which is adapted to engage the damper lever and elevate and lower the same in accordance with the movements of the member 20, in a well known manner to thereby regulate the draft. The member 20 is provided at its lower end with a flange 22 between which and the upper end of the tube 17 is secured the upper plate 23 of the bellows 10.

From the preceding description, it will be seen that when the pressure within the heating system falls below atmosphere, the flexible sheet metal bellows 10 will contract, thus lowering the member 20 and the upper plate 23 of the bellows. This contraction will continue until the main valve 16 becomes seated on the valve seat 15 and the amount of permissible contraction can be regulated as desired by properly locating the valve 16 with respect to the valve seat 15, in normal position of the parts. After 95 100 the valve 16 is seated, it is apparent that no further contraction is permitted even though the pressure within the system may be lowered to a still greater extent and in this way, the bellows are effectively prevented from 105 severe contraction and consequent destruction.

As the pressure within the system again rises, it is necessary to equalize the pressure of the system as a whole with the pressure 110 within the bellows and for this purpose, I have provided a ball check or relief valve

24 which is adapted to coöperate with another valve seat 25 formed on a perforated partition 26 within the tube 17. At the upper end of the tube 17, are provided openings 27 which communicate with the interior of the bellows so that, as the pressure rises within the system to a point where the damper regulator is set to operate, the check valve 24 will be raised, thus equalizing the pressure and then permitting the main valve 16 to be opened and placing the regulator in proper operation.

From the preceding description, it will be seen that the regulator which I have provided is of simple construction and positive in its operation, effectively preventing collapse or destruction of the bellows regardless of the degree of vacuum which may occur in the heating system.

20 Although I have herein shown and described what I now consider the preferred embodiment of my invention, the same is merely illustrative, and I contemplate all changes and modifications that come within 25 the scope of the claims appended hereto.

I claim:

1. In a regulator of the character described, the combination with a bellows adapted to be employed with a vacuum heating system and have its interior placed in communication with said system, of a valve seat, a main valve coöperable with said seat and operated by the contraction and expansion of the bellows, said valve when seated shutting off communication between the interior of the bellows and the heating system, and a relief valve associated with said main valve.

2. In a regulator of the character described, the combination with a bellows adapted to be employed with a vacuum heating system and have its interior placed in communication with said system, of a valve seat, a valve coöperable with said seat and, 45 when in closed position, shutting off communication from the interior of the bellows with the heating system, and a member attached to and movable in unison with a portion of the bellows by which said valve is carried, said valve, when seated, thereby limiting the contraction of the bellows.

3. In a regulator of the character described, the combination with a bellows adapted to be employed with a vacuum heating system and have its interior placed in communication with said system, of a valve seat, a valve coöperable with said seat and, 55 when in closed position, shutting off com-

munication from the interior of the bellows with the heating system, a member attached to and movable in unison with a portion of the bellows by which said valve is carried, said valve, when seated, thereby limiting the contraction of the bellows, and a check valve carried by said member.

4. In a regulator of the character described, the combination with a bellows carried by a pipe member adapted to be attached to a heating system to thereby place the interior of the bellows in communication with said system, said bellows having a top wall, of a valve seat located within said pipe member, a depending rod extending from the inner surface of said top wall of the bellows and movable in unison therewith, said rod being provided with a valve adapted to coöperate with said valve seat and close communication from the interior of said bellows with the heating system, the valve when seated preventing further contraction of the bellows.

5. In a regulator of the character described, the combination with a sheet metal bellows carried by a pipe member adapted to be attached to a heating system, of a valve seat disposed within said pipe member, a hollow tube extending from the inner side of the top wall of said bellows down within the pipe member, said hollow tube being provided with a main valve adapted to coöperate with said valve seat, a check valve located within said tube, said tube being provided with an opening above the check valve to permit communication between the interior of the tube above the valve and the interior of the bellows.

6. In a regulator of the character described, the combination with a bellows adapted to be employed with a vacuum heating system and have its interior placed in communication with said system, of a main valve seat, a main valve coöperable with said seat and adapted, when the valve is seated, to shut off communication between the interior of the bellows and the heating system, and an auxiliary check valve governing communication with the interior of said bellows and adapted to break the vacuum therein.

In witness that I claim the foregoing I have hereunto subscribed my name this 3rd day of May, 1917.

CHARLES METCALF.
